UNITED STATES PATENT OFFICE.

EDWIN M. BASSLER, OF CHICAGO, ILLINOIS, ASSIGNOR TO BAYLEY MFG. CO., OF MILWAUKEE, WISCONSIN, A CORPORATION OF WISCONSIN.

CENTRIFUGAL FAN.

1,184,300.

Specification of Letters Patent.

Patented May 23, 1916.

Application filed May 10, 1913. Serial No. 766,716.

To all whom it may concern:

Be it known that I, EDWIN M. BASSLER, a citizen of the United States, and a resident of Chicago, in the county of Cook and State 5 of Illinois, have invented a certain new and useful Improvement in Centrifugal Fans, of which the following is a specification.

This invention relates to centrifugal fans and relates particularly to runners therefor.

10 The primary object of the invention is to provide an improved fan runner which will be of light weight, strong and durable in construction, effective in operation, and relatively inexpensive.

15 A further feature of my invention relates to a fan construction particularly designed for fans of extreme width and diameter. Heretofore, so far as I am aware, such fans have consisted of a series of separate spiders, varying from two to five, each consisting of cast iron hubs and steel or wrought iron spokes usually formed by T-irons, the inner ends of which are cast directly into the hubs of the spiders, and the vanes or 25 blades of the fan being secured to spokes of each spider and being continuous from side to side of said fan.

It is found in practice that it is practically impossible to cast the spiders so that 30 the spokes thereof will run true or to finish said runners so that the shaft bearings in the hubs of the different spiders will be in alinement. As a consequence, either the fan or the fan shaft is sprung out of shape, 35 throwing the same out of balance and causing the same to run out of true. As a further consequence, in constructing and erecting fans of this character, it is found necessary, after boring the hubs and truing 40 up the spokes, to mark each vane or blade of the fan for punching the rivet holes separately and directly from the holes in the spokes to which they are to be secured, thus necessitating setting the fan up in the shop 45 for the purpose of marking the vanes or blades and then taking the fan apart for shipment and reassembling it on the job where it is to be used. As it relates to this 50 feature; the object of my invention is to overcome the foregoing objectionable features by providing a fan construction for large fans whereby all parts of the fan will be uniform and may be finished complete at the shop ready for erection on the job,

all rivet holes being formed by means of 55 templets.

To effect the foregoing objects, my invention comprises the various features, combinations of features, and details of construction hereinafter described and claimed. 60

In the accompanying drawings, in which my invention is fully illustrated—Figure 1 is a side view of a fan runner embodying my invention; Fig. 2 is a sectional view thereof on the line 2—2 of Fig. 1; Fig. 3 is 65 a fragmentary sectional view illustrating a modification; and Fig. 4 is a side view of a fan runner illustrating a fan construction for large fans.

I will first describe in detail the fan runner shown in Figs. 1 and 2 of the drawing. Said fan runner comprises a hub 1 which is provided with an axial bore 2 to receive the fan shaft and with a keyway 3 for securing said key to said fan shaft, and 4 designates 70 a rim which is preferably made of sheet steel or other suitable sheet metal, and which is connected with the hub 1 by means of spokes 5 made of rods or wires the outer ends of which are secured to the rim 4 and 75 the inner ends of which are secured to the hub 1. As shown, the extreme ends of the spokes are bent substantially at right angles, as shown at 6, the length of said bent-over portions of said spokes being substantially 80 equal to the thickness of the rim 4, and formed at the ends of said bent-over portions 6 are heads 7, the headed outer ends 85 of said spokes being connected into bayonet slots 8 formed in said rim 4. 90

The inner ends of the spokes 5 are adapted to be secured to the hub 1 in any desired manner. As shown, the inner ends of said spokes extend through holes formed in lugs 9, 9' which form spaced series extending 95 around said hub symmetrically on both sides of the plane of the rim 4 and threaded to the ends of said spokes are nuts 10 which provide convenient means for truing up said rim and for tightening said spokes and 100 for adjusting the tension thereof in order to distribute the load uniformly among the different spokes. As shown, the lugs forming each series are staggered relatively to the lugs forming the other series. 105

With the described construction, it is obvious that the spokes 5 will form two series connected to the hub 1 at spaced points and

which converge outwardly to the rim 4. Preferably, also, the spokes 5 are tangent to a circle concentric with the hub 1, and connected to each lug 9, 9' are two spokes 5 which are produced in opposite directions from their points of tangency to said circle, alternate spokes on the rim being connected to lugs of different series.

Secured to the rim 4 are the fan blades or 10 vanes 11. In the preferable construction shown, said vanes or blades 11 are concave on their front sides and are secured to the rim 4 by flanges 12 at the inner ends thereof which are riveted to said rim, the vanes on 15 opposite sides of said rim being preferably arranged in pairs and each pair thereof being secured to said rim by the same rivets.

As shown, the outer ends of the blades or 20 vanes 11 are given a slight set forwardly, as best shown in Fig. 2, which, with the dish 25 of said blades or vanes, renders them very strong to withstand the pressure to which they are subjected in use. Where the fan is designed for developing high pressures, I 30 contemplate strengthening said blades further by securing side plates to the outer ends thereof. This construction is shown in Fig. 3 of the drawings, in which 4' designates the 35 rim of the runner, 5' the spokes, 11' the fan blades or vanes, and 13 side plates secured to the outer ends of said blades or vanes, convenient means for securing said side plates 13 to the outer ends of said blades or vanes consisting of flanges formed on the 40 outer ends of said blades or vanes to which said side plates 13 are riveted in substantially the same manner as the inner ends of said blades or vanes are riveted to the rim 4.

As my invention relates to an improved 45 construction for large fans, I attain the object of my invention by employing a fan made up of a plurality of units each complete in itself and substantially similar in construction to the fan runner shown in Figs. 1 and 2. In Fig. 4 of the drawings,

I have shown a runner of this character, comprising three separate units, each designated, as a whole, A, which are keyed to the fan shaft *a*, with the adjacent ends of the blades or vanes of adjacent runners terminating substantially in the same plane.

As previously stated, each of the units A is substantially identical in construction with the fan runner shown in Figs. 1 and 2, and need not, therefore, be further described.

I claim:—

1. A runner for a centrifugal fan, comprising a hub provided with a shaft opening, a rim consisting of a sheet metal ring disposed edgewise in a plane substantially at right angles to the axis of said hub, wire spokes which connect said hub and rim, and vanes secured to and which project laterally from said rim, the relation being such that said runner will be open inside of its rim, thus permitting air to pass freely therethrough, substantially as described.

2. A runner for a centrifugal fan comprising a plurality of separate units each of said units comprising a hub provided with a shaft opening, a rim consisting of a sheet metal ring disposed edgewise in a plane substantially at right angles to the axis of its hub, wire spokes which connect said hub and rim, and vanes secured to and which project laterally from said rim, the relation being such that said runner will be open inside of said rim, thus permitting air to pass freely therethrough, substantially as described.

In testimony that I claim the foregoing as my invention, I affix my signature in the presence of two subscribing witnesses this 19th day of April, 1913.

EDWIN M. BASSLER.
